UNITED STATES PATENT OFFICE.

DAVID J. FARMER AND SAMUEL FARMER, OF ELIZABETH, NEW JERSEY.

FLUID-PRESSURE REGULATOR.

SPECIFICATION forming part of Letters Patent No. 592,197, dated October 19, 1897.

Application filed August 27, 1896. Serial No. 604,083. (No model.)

To all whom it may concern:

Be it known that we, DAVID J. FARMER and SAMUEL FARMER, citizens of the United States, and residents of Elizabeth, county of Union, and State of New Jersey, have invented certain new and useful Improvements in Automatic Gas-Governors, of which the following is a specification, reference being had to the accompanying drawings, forming a part thereof, in which similar letters of reference indicate corresponding parts.

Our invention relates to improvements in differential automatic gas-governors adapted to be operated by liquid weight and for controlling the supply of gas to the mains, the object thereof being to provide a device of this character which is serviceable and operative under all conditions of pressure; furthermore, to supply an apparatus adapted for obviating the difficulties in adjustment heretofore met with in devices of this character.

A further object is to supply a governor which is susceptible of differential adjustment to meet the varied requirements of gas plants and which will efficiently act under conditions of maximum as well as minimum pressure.

In automatic governors where fluid weight is employed and transferred from one vessel to another for change of pressure, much difficulty has been heretofore experienced in adjusting the fluid weight to insure prompt automatic change of pressure. In our improved governor prompt automatic change of pressure is brought about partly by means of an adjustable plunger located within the fluid-receptacle and partly by means of a compound-valve seat, as will be hereinafter fully described, and specifically set forth in the annexed claims.

In the accompanying drawings, forming part of this specification, Figure 1 is a vertical sectional elevation of the governor. Fig. 2 is an end elevation of the upper portion thereof. Fig. 3 is a side elevation of the governor, illustrating a slightly-modified form thereof. Fig. 4 is a diagram in section of the valve and the fluid-receptacles, illustrating the relative position of the parts when the valve is open; and Fig. 5 is a similar view with the valve closed.

In the practice of our invention the body

or base of the governor comprises a preferably globe-shaped casing A, through which the gas is adapted to pass from a source of supply to the street-mains. The compound-valve seat forming part of our invention is located centrally of this said casing and gas is supplied thereto through the medium of the flanged inlet A' and passes therefrom into the mains through the flanged outlet A², these said two openings being adapted for attachment to pipes leading, respectively, from the source of supply and to the mains.

The compound valve comprises two valves B and B', mounted upon a vertical rod C and operated within downwardly-projecting seats D, which form an integral part of the casing A. Surrounding these seats are sliding collars E, adapted for adjustment vertically upon the seats for the purpose of controlling the supply of gas therethrough, whereby the valves may be caused to travel downwardly to variable distances before the maximum supply of gas is allowed to pass into the mains from the source of supply, as will be herein-after more fully described.

Projecting upwardly and centrally from the upper wall of the casing A is a tube F, through which the valve rod or stem C passes. Surrounding this said tubular projection F is a cylindrical chamber F', upon which is mounted the water-tank G. This said tank is provided with a centrally-located and upwardly-projecting tubular opening G', through which passes the tube F and the valve-stem C. The cock H is tapped into the chamber F' for the purpose of drawing off any overflow of water or other liquid adapted for filling the tank G.

Tapped into the casing A is a tube a, which communicates with a globe-valve a', and leading from this said valve into the chamber F' is a tube or pipe a², whereby gas may pass from the main into the casing A and thence through these said pipes into the chamber F' for operating a float I, which is mounted upon the valve-stem C. This said float is cylindrical in shape and the lower end thereof is open, whereby when the tank G is filled with water or other suitable fluid matter an effectual seal for the gas is provided. For the purpose of lubricating the valve-stem C an oil-tube i is led through the head of the float I.

- Securely fitted to the upper edge of the tank G is a dome or cover G², and the operative mechanism of the governor is mounted thereon. This said mechanism comprises, 5 primarily, fluid-receptacles J and J', which said receptacles are designated as "weight vessels" and are adapted to receive the mercury j or other fluid matter adapted for operating the device, as will be hereinafter fully 10 described. Of these said fluid-weight vessels, the centrally-located vessel J is mounted upon the valve-stem C, and the vessels J' are suspended from cross-rods k, forming part of the oscillating wheels K, which said wheels 15 are mounted upon shafts K' through the medium of antifriction-rollers k', whereby the device can be operated with a minimum of friction. These said parts are all located between uprights L, which are securely mounted 20 upon the dome G² of the tank G.
- The vessels J' are preferably closed at each end, and they are suspended from the cross-rods k by means of slotted hangers M and adjusting-screws M', which said screws are 25 threaded through the head portions of the hangers and bear against the cross-rods k for the purpose of vertically adjusting the vessels J'. The liquid-weight vessel J is open at its upper end and has an adjustable plunger 30 J² located therein. This said plunger is adjustably secured to the valve-stem C by any suitable means, but preferably by means of a nut j', which engages with a thread j² of the valve-stem C. This said nut engages loosely 35 with an aperture in the head of the plunger, whereby the said plunger can be adjusted vertically without having rotary motion imparted thereto. The said vessels J and J' are connected to each other by means of flexible 40 tubes N, and these said tubes are supplied with stop-cocks n for controlling the flow of fluid when desirable.

As a means for supporting the valve-stem and its connected parts, a vertically-adjustable nut c engages therewith. This said nut is provided with projecting arms c', which bear upon antifriction-rollers c², mounted upon cross-rods secured to the wheels K. The upper end of the valve-stem C is provided 45 with a cup-shaped receptacle C', adapted to receive weights for balancing and adjusting the apparatus. Weight receptacles or troughs O are also suspended from the wheels K by means of rods o for a similar 50 purpose.

As a means for setting or properly adjusting the fluid matter within the fluid-receptacles, these said receptacles are each provided upon their bottom surfaces with projections 55 j³, adapted for engagement with a straight-edge, as will be hereinafter described.

In Figs. 1, 2, 4, and 5 of the drawings we have illustrated but three fluid-weight receptacles, but we do not confine ourselves to the 60 specific number thereof. For instance, as illustrated in Fig. 3 of the drawings, two centrally-located vessels J³ are used, and their

plungers J⁴ are operated for vertical adjustment through the medium of screws J⁵, which are threaded through the head j', covering 70 the vessels.

In the operation of the governor, the movement of the valves is effected or actuated by the float I, which is controlled by the pressure in the service-mains through the pipes 75 a and a².

In Fig. 1 the governor is shown in position for day service, or when the minimum of gas is being passed through the valves to the street. It will be observed that the vessels 80 J' are below the vessel J and they contain all the fluid and sustain the valves B and B' in their upward position, whereby a minimum supply of gas is supplied to the street-mains.

When consumption increases or there is a 85 call for more gas in the district, the pressure is reduced in the mains, which causes the float I to descend by gravity. The weight fluid in the vessels J' then begins to flow from the said vessels to the vessel J, and a gradual 90 change of weight of the vessel J causes the valves to descend, whereby an increased volume of gas is allowed to pass into the mains and the pressure therein is increased.

The collars E, surrounding the valve-seats 95 D, may be set so as to cause the valves to drop slowly for either a short or long distance before giving out the full volume or maximum supply of gas, whereby full-weight pressure is not supplied to the mains until the 100 valves are below the lower edges of the collars E, as clearly illustrated in the diagram Fig. 4, and all the weight fluid is transferred from the vessels J' to the vessel J. The valve is then supplied with its maximum 105 weight and full maximum pressure is delivered to the mains.

When the consumption is diminished and lights are being turned out in the district, the float begins to rise by the back pressure in the 110 mains, and upward movement of the valves will be continued until the maximum pressure in the mains causes the valves to assume the position illustrated in the diagram of Fig. 5, whereby the minimum supply of gas is permitted to enter the mains and the weight fluid 115 is gradually transferred back to the vessels J'. 120

In order that the advantages of our improvement may be better understood, we will describe the method of putting the governor into 125 working operation.

After the governor is set up and the working parts are in readiness, the vessels J' are supplied with the proper weight of liquid that is necessary to be transferred for change of 130 pressure. The valve a' is then opened and the gas is passed through the governor to the street and after allowing time for pressure in the mains to settle, as ascertained by the gage. If the pressure maintained is too much for the minimum of consumption, shot or other weight is placed in the receptacles O, or weights may be secured to the rods o if desired. This weight is added until the pressure is re-

duced as required. After pressure settles, giving out the minimum consumption, the governor is adjusted by placing a straight-edge on the projecting plate J^3 of the vessel J 5 and on a line with the bottom of the vessel. The straight-edge in length extends to the outer vessels J' , which said vessels are lowered or raised by their adjusting-screws until the surface of the fluid therein is on a level 10 with the under side of the straight-edge, which represents the bottom of the plunger vessel J . When this is done, the governor is adjusted to minimum or day pressure. As soon as night 15 pressure is on and the liquid is transferred from the outer vessels to the inner vessel, the governor is giving out its maximum volume of pressure. The straight-edge is then placed on the projecting plates which extend from the vessels J' and on a line with the bottom 20 of said vessels. The liquid in the center vessel is then adjusted for the maximum pressure by the simple operation of raising or lowering the plunger J^2 until the liquid is on a line with the bottom of the straight-edge, and the 25 full adjustment is made accurately for automatic use the first night, and no further adjustment is necessary to meet the requirements of minimum and maximum pressure, and it will be observed that the preliminary 30 and final adjustment is made when the governor reaches its maximum pressure on the first night.

The mechanism we have described for connecting and operating the fluid-weight vessels may be varied if found necessary without departing from the scope of our invention, and we do not confine ourselves to arrangement of the two outside liquid vessels J' , as it is obvious that one vessel may be made to encircle the plunger vessel J for carrying the liquid weight to be transferred to said plunger vessel.

Having thus described our invention, what we claim as new, and desire to secure by Letters Patent, is—

1. An automatic gas-governor, comprising a plurality of fluid-weight vessels, and means for connecting them to each other and for transferring the fluid weight, a valve, a projecting valve-seat and an adjustable collar thereon, the stem of the said valve having a float thereon engaging with a tank adapted to contain water or other fluid for sealing the gas, and a vertically-adjustable plunger 50 mounted on the valve-stem for adjusting the fluid weight, the said plunger located within one of the fluid vessels; and means for inclosing, supporting and mounting the said parts, for the purpose set forth.

2. In an automatic gas-governor, the combination of a valve and projecting valve-seats, the seats having sliding collars thereon for regulating the flow of gas, and a float and one or more fluid-weight vessels secured to the 65 stem of the said valve, said vessels having vertically-adjustable plungers therein for adjusting the fluid weight, a plurality of fluid-

weight vessels communicating with the other said vessels and means for adjustably operating them, a casing surrounding the said valve and a tank inclosing the said float, substantially as shown and described.

3. A differential automatic gas-governor comprising a body portion having an inlet thereto and an outlet therefrom, and downwardly-projecting valve-seats therein, having adjustable collars thereon, and a double valve for engagement with said seats and collars, and a valve-stem which is suspended from friction-rollers located between two revolute disks or wheels, said stem having a float secured thereto which is located within a tank for sealing the gas, said tank communicating with a receptacle which connects with the outlet portion of the said body, said stem also having a fluid-weight vessel secured thereto with an adjustable plunger therein; and vertically-adjustable fluid-weight vessels communicating with the other said weight vessel, these said vessels being suspended between the said wheels which support the valve-stem, whereby the fluid-weight vessels will be alternately raised or lowered for transferring the weight fluid and for governing the supply of gas for the mains, substantially as 95 and for the purpose shown and described.

4. In an automatic gas-governor, a fluid-weight vessel having an adjustable plunger therein for raising and lowering the surface of the fluid weight, said vessel being secured to the valve-stem of a gas-governor, combined with fluid-weight vessels for transferring and operating the said parts, substantially as and for the purpose set forth.

5. The combination in an automatic gas-governor of fluid-weight vessels having adjustable plungers therein, secured to the valve-stem of the governor; with auxiliary fluid-weight vessels and means for supporting and adjusting them, substantially for the purpose shown and described.

6. The combination in a gas-governor, of a double valve and double-valve seats, said seats being vertically adjustable, the stem of the said valve having a float thereon, also a fluid-weight vessel having an adjustable plunger therein, said vessel communicating with adjustable vessels for transferring the fluid weight; with a rock-shaft mechanism for supporting and moving the said parts, substantially as and for the purpose shown and described.

7. In an automatic gas-governor, a fluid-weight vessel having an adjustable plunger therein for raising and lowering the surface of the fluid weight, said vessel being connected to the valve-stem of a gas-governor, combined with fluid-weight vessels for transferring the fluid weight, for the purpose shown and described.

8. The combination with a gas-governor, of projecting valve-seats, said seats being provided with collars or casings surrounding said valve-seats, said collars adapted to be moved

up and down on the seats to regulate the flow of gas to the main, substantially as shown and described.

9. In automatic governors where fluid weight is used and transferred from one vessel to another, means for adjusting said vessels in proper vertical relation to each other, said means comprising plates projecting from the bottoms of said vessels, or their equivalents and adapted to be used as supports upon which to apply a straight-edge for adjusting the same in any desired vertical relation to each other, as described and set forth.

10. In automatic governors where fluid weight is used and transferred from the ves-

sel mounted on the valve-stem to other movable fluid-weight vessels, a vertically-movable plunger mounted on said stem traveling therewith and arranged in said fluid-weight vessel, and adapted to be so adjusted thereon as to change the weight of the liquid in said vessel, substantially as shown and described.

In testimony that we claim the foregoing as our invention we have signed our names, in presence of two witnesses, this 19th day of August, 1896.

DAVID J. FARMER.
SAMUEL FARMER.
